UNITED STATES PATENT OFFICE.

WILLIAM HENRY MORGAN, OF ALLIANCE, OHIO.

OVERHEAD TRAVELING CRANE.

SPECIFICATION forming part of Letters Patent No. 585,277, dated June 29, 1897.

Application filed July 15, 1896. Serial No. 599,243. (No model.)

To all whom it may concern:

Be it known that I, WILLIAM HENRY MORGAN, of Alliance, in the county of Stark and State of Ohio, have invented certain new and useful Improvements in Overhead Traveling Cranes; and I do hereby declare the following to be a full, clear, and exact description of the invention, such as will enable others skilled in the art to which it appertains to make and use the same.

My invention relates to an improvement in overhead traveling cranes, and is designed more particularly for carrying ladles, the object being to provide devices which when ladle is elevated, as when discharging into a converter, holds the ladle-suspending devices rigidly against movement, but which are disengaged from said suspending devices when the ladle is lowered.

With these ends in view my invention consists in the parts and combinations of parts, as will be more fully explained, and pointed out in the claims.

In the accompanying drawings, Figure 1 is a view in transverse section through a bridge, showing a trolley thereon embodying my invention. Fig. 2 is a view in side elevation of same, and Fig. 3 is a view in section through one of the guides.

A represents an elevated trackway running lengthwise the shop on which the bridge travels. This bridge is composed of end carriages C (only one of which is shown) and two girders D, preferably box-girders. Secured to the upper surfaces of the girders D are the rails E, constituting a trackway on which the trolley F runs. This trolley F is propelled lengthwise the bridge in the usual manner by an electric motor and suitable gearing, and is provided near its opposite sides with the hoisting-drums G, which latter extend in the direction of the length of the bridge and are so located with relation to the bridge-girders that the hoisting-chains G' pass downwardly on the outer side of the girders D. The two drums G are actuated by the electric motor H, carried by the trolley F, preferably at a point between the drums and geared to the drums in the manner shown, so that both drums are actuated simultaneously to wind and unwind equal lengths of chain. The gearing shown comprises a pinion 1 on

the armature-shaft of the motor, meshing with the pinion 2, fast on shaft 3. The pinion 2 meshes with the pinion 4 on shaft 5, and at its other end is a pinion (not shown) which meshes with the pinion 6. The shafts carrying the pinions 4 and 6 are each provided with a pinion, the one on shaft 5 meshing with the toothed wheel 7, fast to one drum, while the shaft carrying pinion 6 also carries a pinion (not shown) which meshes with the toothed wheel 8, fast to its drum. The trolley is provided near its front and rear ends with the transverse girders I, which latter project at both ends beyond the bridge-girders for the attachment of the depending guides J. These guides project below the bridge-girders and are secured at their upper ends to the girders I and are suitably braced on their outer sides to prevent them from spreading. These guides have flanges a and are formed with slightly-flaring mouths b.

Each drum carries two chains G', which latter are secured at their lower ends to the upper ends of the bail L. This bail can be of any approved construction, but is preferably provided at each side or end thereof with a frame M, to which the lower ends of the chains G' are secured. Each frame carries at its upper end, at its opposite sides, two antifriction-rollers d, which latter project beyond the sides of the frame and adapted when the latter are elevated to enter the guides J, the rollers being partly overlapped by the L-shaped flanges a of the guides. Each frame is also provided on its outer face with the vertical guiding-strips a', forming a guiding-groove within which the roller b of its respective guide rests when the frame is in its elevated position.

In a crane designed for carrying ladles it is desirable to support the ladle by flexible devices, so that when the ladle is lowered it can be readily moved and handled and also to enable the ladle to yield or give in the event it comes in contact with an obstruction while being transported from one part of the mill to another. When, however, the ladle is in its elevated position for discharging its contents into a converter, it is essential that its bail be held immovable or rigid, so as to overcome the tendency of the ladle to swing while being tilted. This is accomplished by

the guides J and frames M above described. When the frames M are below the guides J, the bail and ladle carried thereby are supported solely by the flexible chains. Hence 5 the ladle is free to be moved and free to swing. When, however, the frames M enter with the grooves, the bail then becomes locked against lateral movement, thus rigidly holding the ladle in position to be tipped for discharging its contents.

In the drawings I have shown in dotted lines the ladle discharging into a converter, and while the construction described is admirably adapted for use in connection with a 15 converter I do not intend to be understood as so limiting its application, as the device is equally well adapted for pouring metal direct into molds.

For tilting the ladle I employ an auxiliary 20 trolley O, which latter travels on the track-way O', formed on the lower flanges of the bridge-girders. This trolley carries a hoisting drum and chain, which latter is designed to engage a ring or hook on the underside of 25 the ladle and tilt the latter while the bail carrying same is held against movement.

I can, if desired, locate the guides between the bridge-girders instead of on the outside of same, and instead of employing an auxiliary 30 trolley for tilting the latter result can be accomplished by an auxiliary drum on the hoisting-trolley.

It is evident that changes in the construction and relative arrangement of the several 35 parts might be made without avoiding my invention, and hence I would have it understood that I do not restrict myself to the particular construction and arrangement of parts shown and described; but,

40 Having fully described my invention, what I claim as new, and desire to secure by Letters Patent, is—

1. In an overhead traveling crane, the combination with a bridge and a traveling trolley 45 thereon, of a hoisting-chain carried by the trolley and carrying a ladle, a guide depending from the trolley, and means carried by the ladle-supporting bail adapted to enter the 50 guide and lock the bail, substantially as set forth.

2. In an overhead traveling crane, the combination with a bridge and a traveling trolley thereon, the trolley having flexible hoisting devices, of guides depending from the trolley, 55 a ladle having a bail and devices carried by the bail and adapted to rest in the guides when the ladle is in its elevated position, substantially as set forth.

3. In an overhead traveling crane, the combination with a bridge and a traveling trolley thereon, the trolley having two hoisting drums and a chain on each drum, of guides depending from the trolley, a ladle, and devices carried by the ladle-bail and adapted to

rest in the guides when the ladle is in its elevated position, substantially as set forth. 65

4. In an overhead traveling crane, the combination with a bridge and a traveling trolley thereon, the trolley having two hoisting-drums and a chain on each drum, of guides 70 outside of the bridge-girders and depending from the trolley, a ladle and devices carried by the ladle-bail and adapted to rest in the guides when the ladle is in its elevated position, substantially as set forth. 75

5. In an overhead traveling crane, the combination with a bridge and a traveling trolley thereon, of flexible hoisting devices carried by the trolley, ladle-carrying frames connected to the hoisting devices and guides depending from the trolley and adapted to be engaged by the ladle-carrying frames when the ladle 80 is in its elevated position.

6. In an overhead traveling crane, the combination with a bridge and a traveling trolley 85 thereon, of hoisting devices carried by the trolley ladle-carrying frames connected to the hoisting devices, guides depending from the trolley and adapted to be engaged by the ladle-carrying frames when the ladle is in its 90 elevated position and a second trolley carrying a chain for tilting the ladle, substantially as set forth.

7. In an overhead traveling crane, the combination with a bridge and a traveling trolley 95 thereon, of two hoisting-drums, gearing for simultaneously actuating the drums, a hoisting-chain on each drum, two guides depending from the trolley two frames rigidly secured to and constituting a part of the ladle-bail, the said frames adapted to enter the guides as the ladle is elevated and lock the ladle against lateral movement, substantially 100 as set forth.

8. In an overhead traveling crane, the combination with a bridge, a traveling trolley thereon, and hoisting devices and two guides carried by the trolley, of a bail, two frames integral therewith and connected to the hoisting devices, and antifriction-wheels carried 110 by the frames and adapted to engage the sides of the guides, substantially as set forth. 105

9. In an overhead traveling crane, the combination with a bridge, a traveling trolley thereon, hoisting devices and two guides carried by the trolley, and an antifriction-roller carried by each guide, of a bail carried by the hoisting devices, and two frames secured to the bail each frame having two antifriction-rollers thereon, substantially as set forth. 115 120

In testimony whereof I have signed this specification in the presence of two subscribing witnesses.

WILLIAM HENRY MORGAN.
